UNITED STATES PATENT OFFICE.

HOWARD R. LEE AND KENT R. COCHRAN, OF SAN FRANCISCO, CALIFORNIA.

COMBINED FIRE-EXTINGUISHER AND SALVAGING DEVICE.

1,320,012.

Specification of Letters Patent.

Patented Oct. 28, 1919.

Application filed December 16, 1918. Serial No. 267,738.

To all whom it may concern:

Be it known that we, HOWARD R. LEE and KENT R. COCHRAN, citizens of the United States, residing in the city and county of

5 San Francisco and State of California, have invented a certain new and useful Improvement in a Combined Fire-Extinguisher and Salvaging Device, of which the following is a specification.

10 Our invention relates to improvements in a combined fire extinguisher and salvaging device for vessels and the like wherein a flask operates in conjunction with means for liberating gas into a collapsed container; and the objects of our invention are—

First, to provide an improved device adapted to inflate a ship's compartment when said compartment has become flooded;

Second, to provide an improved device of 20 the character described adapted to liberate a fire-extinguishing gas when the temperature of the compartment within which the device is contained attains a predetermined temperature.

25 We accomplish these several objects by means of the device disclosed in the drawings forming a part of the present specification wherein like characters of reference are used to designate similar parts throughout the said specification and drawings, and in which—

Figure 1 is a transverse sectional view of a vessel disclosing our improved device applied to several compartments thereof;

35 Fig. 2 is a vertical sectional view of one of the ship's compartments disclosing the manner in which a collapsed container is detachably retained within the upper portion of said compartment;

40 Fig. 3 is a broken vertical sectional view of a compartment taken at right angles to Fig. 2, disclosing the operating float;

Fig. 4 is a broken sectional view on an enlarged scale, of one of the gas flasks, taken 45 on line 4—4 of Fig. 5 of the drawings, in the direction indicated; and

Fig. 5 is a horizontal sectional view taken on line 5—5 of Fig. 4 of the drawings, in the direction indicated.

50 Referring to the drawings the numeral 1 is used to designate a collapsible container of any suitable water and air tight fabric, normally folded and detachably retained in the upper or unoccupied portions of a ship, such as the state-rooms 2 or cargo spaces 3 of a ship or vessel 4. The container 1 is

detachably supported in position by means of flexible slats 6 whose ends rest upon battens 7 secured in any suitable manner to the upper portion, deck or ceiling of a compartment, as disclosed in Figs. 1 and 2 of the drawings.

A flask, 8, preferably of metal construction to contain a gas under pressure, such as carbon-dioxid, is secured in any suitable manner adjacent and connected to the collapsed container 1.

The flask 8 has screw-threaded to the neck thereof a centrally apertured sleeve 9 which holds a disk 11 of copper or other soft metal over the neck of said flask 8 to normally retain the gas therein under a certain pressure and arranged to give way and thereby liberate the gas within the flask 8 under an increased pressure, the purpose of which will hereinafter be more fully described.

The neck or entrance of the collapsible container 1 is secured to the sleeve 9 of the flask 8 whereby communication between said flask 8 and said container 1 may be established when the disk 11 is ruptured or punctured.

A counter shaft 12 is rotatably mounted within the sleeve 9 and adjacent the central bore thereof. An arm 14 is secured to the counter shaft 12 and projects through a pocket or recess 16 into the central bore of the sleeve 9. A barb 17 is pivotally connected to the arm 14 and is arranged to puncture the disk 11 when said arm 14 is moved downward.

A lever 18, having a float 19 on the outer end thereof, is connected to one end of the counter shaft 12, the weight of said lever 18 and float 19 normally tending to retain the barb 17 away from the disk 11.

A suitable guard 20 may be placed around the lever 18 and float 19 thereon to prevent interference with the operation of said float and lever.

In operation it is intended to place collapsed containers 1 with their connected flasks 8 in the upper portion of all unoccupied portions of a vessel or the like so as not to detract from or decrease valuable cargo space.

In cases of sinking the flooding of the compartment will operate the float 19 and lever 18 and puncture the disk 11 thereby releasing the compressed gas into the container 1. The increased pressure of the gas within the container 1 will bend the slats 6,

as disclosed in Fig. 2 of the drawings, until one or both ends of said slats 6 are removed from the supporting battens 7. This will release the container into the compartment and permit its inflation from the gas within the flask 8 until said gas pressure within the inflated container is equal to the pressure of the surrounding water.

In this manner all containers within 10 flooded compartments will be inflated to increase the buoyancy of the sinking vessel and thereby salvage the same, or keep said vessel afloat until it can be towed to port for repairs.

15 In case of fire the heat within the compartment will increase the pressure of the gas within the flask and rupture or blow out the disk 11 which will also liberate the gas into the container 1. If the container 20 is destroyed by the fire the carbon-dioxid gas, being heavier than air, will descend and displace the oxygen containing atmosphere from the vicinity of the conflagration.

25 As carbon-dioxid gas is a well known fire-extinguishing element it is obvious that the conflagration will be extinguished.

If the container 1 is not destroyed by the fire said inflated container will fill the compartment and tend to smother the flame.

30 Having thus described our invention what we claim as new and desire to secure by Letters Patent is—

35 1. A combined fire extinguisher and salvaging device comprising a collapsed inflatable container; means for detachably retaining the collapsed container in the upper

portion of a ship's compartment; a flask connected to the container and containing a gas heavier than air and under pressure; a disk arranged within the neck of the flask 40 to normally retain the gas within the flask under normal pressure and to liberate said gas under an increased internal pressure caused by a rise in temperature; and means for puncturing the disk to liberate the gas 45 when the compartment is flooded.

2. A combined fire extinguisher and salvaging device comprising a collapsed inflatable container; means for detachably retaining the collapsed container in the upper 50 portion of a ship's compartment; a flask connected to the container and containing a gas heavier than air and under pressure; a disk arranged within the neck of the flask to normally retain the gas within the 55 flask under normal pressure and to liberate said gas under an increased pressure; a counter shaft mounted within the neck of the flask and above the disk; an arm connected to the counter shaft; a barb connected to the arm and arranged to puncture the disk when said arm is moved toward said disk; a lever connected to the counter shaft; and a suitable float connected to the lever to operate same and puncture the disk 60 to liberate the gas when said float is raised by water within the compartment.

In witness whereof we hereunto set our signatures.

HOWARD R. LEE.
KENT R. COCHRAN.
